Primary Examiner — Cathron Brooks*Assistant Examiner* — Teddy Falloway(74) *Attorney, Agent, or Firm* — Nath, Goldberg & Meyer; Jerald L. Meyer(57) **CLAIM**

The ornamental design for a interlinking container, as shown and described.

DESCRIPTION

FIG. 1 is a perspective view of an interlinking container showing my new design;

FIG. 2 is a front perspective view thereof;

FIG. 3 is a top view thereof;

FIG. 4 is a bottom view thereof;

FIG. 5 is a right view thereof;

(Continued)

FIG. 6 is a left side view thereof;
 FIG. 7 is a front view thereof; and,
 FIG. 8 is a back view thereof.

1 Claim, 8 Drawing Sheets
